ELECTRICAL SWITCHING SYSTEM

John H. Newitt, Montclair, N. J., assignor to Federal Telephone and Radio Corporation, New York, N. Y., a corporation of Delaware

Application July 2, 1945, Serial No. 602,823

4 Claims. (Cl. 250—27)

1

The present invention relates to electrical switching systems.

In certain types of switches, such as certain types of electronic switches, the switching voltages produce an effect in the output which is undesirable, particularly when the switch is being used for switching audio frequency currents, or when the switch also serves as a detector to translate radio frequency into audio frequency currents.

An object of the present invention is the provision of an improved switching system and method of switching.

Another object of the present invention is the provision of an electronic switching system in which the switching control voltages introduce substantially no effect in the output of the switch.

A still further object of the present invention is the provision of an improved electronic switch which also serves as a detector.

Other and further objects of the present invention will become apparent and the invention will be best understood from the following description of embodiments thereof, reference being had to the accompanying drawings, in which:

Fig. 1 is a schematic and block diagram of an electronic switching system embodying my invention utilizing a push-pull arrangement;

Figs. 2 and 3 are similar diagrams of modified push-pull arrangements embodying my invention; and

Fig. 4 is a similar diagram of a single tube detector and electronic switch embodying my invention.

Referring now to Fig. 1, the electronic switch there illustrated and generally designated by the numeral 1 is used to switch energy from an audio frequency source 2 to a load 3. The switch 1 includes two electron discharge devices, for example triodes 4 and 5 having their grids connected to the opposite ends of the secondary 6 of an audio frequency transformer 7 whose primary 8 is coupled to the output of the audio frequency source 2. The midpoint of the secondary 6 is connected to ground as indicated at 9. The voltages thus impressed on the grids of triodes 4 and 5 will therefore be 180° out of phase with each other. The anodes of triodes 4 and 5 are connected to the opposite ends of the primary 10 of an output transformer 11, whose secondary 12 is connected to the load 3 with the midpoint of the primary 10 being connected by a lead 13 to the positive side of a source of anode potential 14 whose negative side is grounded. The arrangement thus far described is a push-pull amplifier.

Triodes 4 and 5 are biased by means of a voltage-dividing arrangement generally designated by the numeral 15 applied between the positive side of the source of anode potential 14 and ground (the negative side of said source 14). The arrangement 15 includes a series-dropping resistor 16 and a resistor 17, with which is connected movable arms 18 and 19 at selected points thereon, said arms 18 and 19 being connected with the cathodes of tubes 4 and 5 respectively and being also coupled to ground at radio frequency by by-pass condensers 20 and 21 respectively. Arms 18 and 19 are so adjusted as to bias the triodes to cut-off so that the plate current from each of triodes 4 and 5 is substantially zero. If triodes 4 and 5 are identical in characteristics, one arm would suffice for both and a single by-pass condenser would be used for said arm instead of two arms 18 and 19 with two condensers 20 and 21. If, however, the tubes are not quite identical the cut-off point of said triodes may be different and therefore it is advisable to use two separate arms 18 and 19 to separately bias each of the triodes.

The electronic switch 1 is opened and closed by control voltages of negative polarity derived from a source of voltages 22. One side of the output of the source of switching voltages 22 is connected to ground by a lead 23 and the other side is connected through a resistor 24 and a lead 25 to the midpoint 26 of a resistor 27, the opposite ends of which resistor 27 are connected to the grids of triodes 4 and 5. The resistor 27 preferably has greater resistance value than the impedance of the secondary 6 of transformer 1 so that the audio frequency voltages from the source 2 will not be shorted in said resistance. It will thus be seen that the control voltages from source 22 are applied to the grids in phase as contrasted with the signal voltages derived from the audio frequency source 2, which latter are applied 180° out of phase to the gap with respect to each other. Accordingly it will be seen that the effect of the switching control voltages derived from the source 22 has opposed effects in the primary 10 of output transformer 11, so that any voltages produced by said source 22 in the primary 10 would buck each other out and produce no current flow which would affect the load.

It is preferred that the source 22 provide switching control voltages which are negative with respect to ground. Such negative voltages are preferably in the form of rectangular negative pulses, the pulses having a sufficient value to completely block conduction of triodes 4 and 5. The pulses may be in the form of a train

having a regular repetition rate, or the occurrence of said negative pulses may be controlled by a source of synchronizing pulses or the like 28. Between such negative pulses it is preferred that a zero voltage be applied to the grids from the source 22. There are various arrangements for accomplishing this such as, for example, the arrangement described in the copending application of M. C. Dettman-1, for "Blocking Circuit," Serial No. 524,976, filed March 3, 1944, now Patent No. 2,444,678. In said copending application there is described a rectangular wave generator whose output is fed into a D.-C. reinsertion circuit so that the maximum positive level of the rectangular wave pulses is zero D.-C. potential with respect to ground while the negative pulses are substantially negative with respect to ground. Other arrangements may likewise be employed for this purpose. Since triodes 4 and 5 are normally biased to cut-off, that is, in the absence of negative switching voltages from source 22, no plate current flows in the output of said triodes except when the positive halves of signal energy are impressed on the grids thereof. Thus the D.-C. level between switching voltages is zero at the output of the triodes. When the negative voltages from the switching control source 22 are applied to the grids of triodes 4 and 5, they render said grids further negative and no plate current appears in the output of said triodes. Thus it will be seen that under all conditions of switching, no change in the D.-C. level of the output of the triodes is produced and therefore no effect due to the switching voltages appears in said output. The foregoing operation plus the bucking effect of the switching voltages in the primary 10, of output transformer 11, doubly insure that the switching voltages do not cause impulses in the output. This is particularly necessary when the rate of repetition of the switching voltages is at audio frequency.

Another arrangement for controlling triodes 4 and 5 when they are dissimilar and to balance them is illustrated in Fig. 2. In this embodiment, the cathodes of triodes 4 and 5 are connected to opposite ends of the resistor of a potentiometer 29, whose arm is connected to a movable arm 30, adapted to connect to any selected point on resistor 17. It will be seen that by adjusting arm 30, the total bias voltage applied to both cathodes will be determined and by adjusting the arm of potentiometer 29 the bias applied to one of the triodes may be increased while that applied to the other triode may be decreased. Thus if the two triodes are dissimilar, they can be properly balanced to cut-off. Arm 30 and the potentiometer arm are connected to ground through a by-pass condenser 31.

In Fig. 3, the triodes 4 and 5 are illustrated as being in a cathode-follower type of push-pull arrangement, with the anodes of the triodes 4 and 5 being connected to a positive source of anode potential, the negative source thereof being connected to ground. Biasing voltages for the triodes are derived from cathode resistors including the resistor of the potentiometer 29 which is connected at its opposite ends to the cathodes of triodes 4 and 5, the arm of potentiometer 29 being connected in series with a variable resistor 32 to ground, said variable resistor 32 being shunted by a by-pass condenser 33 to ground. An additional cathode resistor 34 is provided in shunt with the resistor of potentiometer 29, resistor 34 serving as a load resistor.

The arm 35 which makes contact with any selected point on resistor 34 is connected by means of a coupling condenser 36 to the load, the other part of the load 3, the other side of the input 5 to the load, being taken from ground as indicated by line 37. By moving arm 35, the relative gain or output derived from triodes 4 and 5 may be varied. Thus if the gain of tubes 4 and 10 5 is non-uniform because said tubes are dissimilar, by adjusting arm 35, the output derived from the triodes 4 and 5 will be balanced.

In Fig. 4 there is illustrated a single tube arrangement including a triode 38 which is used to detect energy from a radio frequency source 15 39 and is likewise used as part of an electronic switch, generally designated by the numeral 40, to switch the radio frequency energy, in translated form, with respect to the load 3. The radio frequency source 39 may be coupled to the triode 20 38 by means of a radio frequency transformer 41 whose primary is connected to the output of source 39 and whose secondary has one end thereof connected to the grid of triode 38, the other end 42 of the secondary being connected through a resistor 43 shunted by a radio frequency by-pass condenser 44 to ground. The negative switching voltages from source 22 are applied at the end 42 of the secondary of transformer 41. Triode 38 should be carefully biased 25 to cut-off. For this purpose the arm 18 which is connected to the cathode of triode 38 is adjusted in relation to resistor 17 of the voltage divider 15. The anode of triode 38 is connected through a load resistor 45 to the positive side 30 of anode potential source 14 with a by-pass condenser 46 connected between said positive side and ground, and the radio frequency output being taken off with respect to ground through a coupling condenser 47 which is connected to the load, the other part of the input of the load 35 being from ground. Since triode 38 is biased to cut-off, the switching voltages will produce no effect in the output thereof as has been explained hereinabove in connection with the arrangement of Fig. 1. Since, however, there is no bucking 40 arrangement, as illustrated in Fig. 1, for cancelling the effects of switching voltages, the adjustment of the bias should be carefully made in the arrangement of Fig. 4.

While I have described other details of embodiments of my invention, it will be apparent to those versed in the art that numerous changes in these details may be made without departing from the teachings of my invention. For example, while I have described the use of triodes and the application of both the switching voltages and the signal voltages between the grid and cathode of said triodes, it will be readily apparent to those versed in the art that other multi-electrode tubes may be used in place thereof with, for example, the signal voltages applied to one control electrode and the switching voltages applied to another control electrode. Various different types of input systems could readily be used 60 in place of those hereinbefore described, as for example, the use of a phase inverter and a resistance coupling for the input to the push-pull arrangement. Accordingly, while I have described above the principles of my invention in connection with specific apparatus, and particular modifications thereof, it is to be clearly understood that this description is made only by way of example and not as a limitation on the scope of my invention as defined in the accompanying claims.

I claim:

1. An electronic switching system comprising a pair of electron discharge devices each including an anode, cathode and control electrode, means for coupling said devices in a push-pull cathode-follower arrangement with the signal voltages being impressed on the control electrodes of said devices 180° out of phase with respect to each other, a source of switching voltages, means for impressing said switching voltages cophasally between the control electrodes of each of said devices and ground to control the conduction thereof, a resistor coupled at the opposite ends thereof to said cathodes, and means for coupling any one of a number of points on said resistor to said load, a second resistor coupled in parallel with said first named resistor, a parallel resistance capacitance network, means for adjustably connecting one end of said network to said second resistor, and means coupling the other end of said network to ground.

2. An electronic switching system for switching signal voltages from a source to a load comprising a pair of electron discharge devices, each including an anode, cathode and control electrode, means coupling said devices in push-pull with the signal voltages being impressed on the control electrodes 180° out of phase with each other, a source of switching voltages, means for impressing said switching voltages between each of said control electrodes and ground substantially in phase and an output circuit comprising an output transformer, means for coupling the anodes of said devices to opposite ends of the primary of said transformer, and means for connecting the midpoint of said primary to a positive pole of a potential source, the secondary of said transformer being coupled to a load, a resistor interconnecting said cathodes, an adjustable parallel resistance capacitance network adjustably coupled at one end to said resistor and connected at the other end to ground.

3. An electronic switching system for switching signal voltages from a source to a load comprising a pair of electron discharge devices, each including an anode, cathode and control electrode, means coupling said devices in push-pull with the signal voltages being impressed on

the control electrodes 180° out of phase with each other, a source of switching voltages, means for impressing said switching voltages between each of said control electrodes and ground substantially in phase, means for biasing said devices to cut-off comprising a voltage divider connected across a source of potential and having one end grounded, a resistor, the opposite ends of which are connected to the cathodes, and a shorting member for connecting a selected one of a number of points on said resistor to a selected one of a number of points on said voltage divider, and a capacitor connected between said member and ground.

15 4. An electronic switching system comprising a pair of electron discharge devices each including an anode, cathode, and control electrode, means for coupling said devices in a push-pull arrangement with the signal voltages being impressed on the control electrodes of said devices 180° out of phase with each other, means for biasing said devices to cut-off so that only positive portions of the applied signal appear in the 20 output of said devices, a source of negative switching voltages of such value as to completely 25 block conduction of said devices, and means for impressing said switching voltages cophasally on the control electrodes of said devices.
